ATTORNEY

Patented June 11, 1929.

UNITED STATES PATENT OFFICE.

HENRY T. GOULD, OF SEATTLE, WASHINGTON.

PENCIL SHARPENER.

Application filed July 11, 1927. Serial No. 205,005.

My invention relates to pencil sharpeners and the primary objects of the invention are to provide a pencil sharpener of very simple and inexpensive design comprising a blade mounted in a novel holder and having a flexible wrapper with a flap that is adapted to serve as a shield for the blade.

With the above and other objects in view which will appear as the description proceeds, 10 the invention consists of the novel construction, combination and arrangement of parts hereinafter described and claimed. These objects are accomplished by devices illustrated in the accompanying drawings; wherein:—

15 Figure 1 is a view in perspective of a pencil sharpener embodying the features of the invention;

Fig. 2 is a view in central longitudinal vertical section of the same;

20 Fig. 3 is a plan view of the flexible wrapper in the unfolded position; and

Fig. 4 is a view in perspective of the blade holder with a blade installed therein.

Referring to the drawings throughout 25 which like reference numerals designate like parts, the numeral 5 indicates a blade that is preferably made of steel in rectangular shape and sharpened on its outer edge. The numeral 6 designates the blade holder as a whole that is preferably made of aluminum, 30 tin, or other thin sheet metal. Referring particularly to Fig. 4 said blade holder comprises a flat horizontal portion 7 that is slanted upwardly at 8 and downwardly at 9 to form 35 upwardly at 8 and downwardly at 9 to form an angular ridge 10. It is then bent backwardly upon itself at 11 to form a pocket 12 wherein the blade 5 is installed with its sharpened edge portion projecting upwardly in a slantwise direction.

40 The numeral 13 designates a wrapper or folder that may be made of a paper composition, leather, or other flexible material. Said wrapper comprises an end portion 14, mid portions 15 and 16 and a flap portion 17. 45 Slits 18 and 19 are cut through the mid portion 15.

To install the blade holder 6 and blade 5 within the wrapper 13 said holder is turned over from the position shown in Fig. 4 with 50 said blade projecting downwardly which is then passed through the slit 18 with the holder

portion 8 bearing against the wrapper portion 15.

The wrapper portion 14 is then folded at 20 over against the blade holder 6 and portion 15 which is bent to conform somewhat to the ridge 10 of said blade holder. The two portions 14 and 15 with the blade holder between 55 are then folded over at 21 against the portion 16.

The device will now be in its normally operative position with the sharpened edge portion of the blade 5 projecting upwardly and slanting forward as clearly shown in Fig. 1 of the drawings. In order to hold the device 65 more securely in this position a metal band 22 is bent around its middle portion with its ends in abutment on the underside. Crimp holes 23 may be punched through said band 70 and wrapper sections to hold same in place.

In practical use the device is placed on a flat surface and the pencil may be readily sharpened by drawing its point across the sharpened edge of the blade as will be readily understood. When not in use the flap 17 may 75 be folded at 24 over the blade 5 and its end 25 passed through the slit 19 as shown in Fig. 2. Said flap will thus serve as a shield for the blade and the device may be safely 80 carried in the pocket.

Having thus described my invention, it being understood that minor changes may be resorted to in its construction without departing from its scope and spirit, what I claim and desire to secure by Letters Patent of the 85 United States is:—

A pencil sharpener comprising a blade holder, said blade holder having a raised portion with slanting sides, a portion of said holder bent back to form a blade pocket on 90 one of said slanting sides, a blade installed in said pocket, a flexible wrapper member having two slits therein, said blade projecting exteriorly of said wrapper through one of said slits in a slantwise direction, and 95 a flap for said wrapper arranged to be inserted in the other slit to serve as a shield for the blade.

In witness whereof I hereunto subscribe my name this 15th day of June, A. D. 1927.

HENRY T. GOULD.
